GARMENT HANGER

Sidney M. Abbens, San Francisco, Calif.

Application January 8, 1941, Serial No. 373,674

2 Claims. (Cl. 223—86)

This invention relates to an improved garment hanger and has particular reference to the association with the hanger of an insect exterminating medium, such as moth balls.

The principal object of the invention is the employment of moth ball holding means that will most effectively retain the moth balls in the hanger and will, at the same time, permit the generated gases or fumes to quickly pass through the hanger to contact and eradicate the troublesome moths.

An additional object of the invention is the provision of a shield or cover for the trouser retaining bar of the hanger that will prevent the accidental displacement of the moth balls from the hanger.

The further object of the invention is the production of a garment hanger that is economical to manufacture, simple in construction, positive in operation, and highly serviceable in use. Other objects and advantages will be apparent during the course of the following description.

In the accompanying drawing forming a part of this specification and in which like numerals are employed to designate like parts throughout the same,

Fig. 1 is a central longitudinal section through the hanger;

Fig. 2 is a front elevational view of the same;

Fig. 3 is a cross section through the hanger, the view being taken on the line 3—3 of Fig. 1;

Fig. 4 is a top plan view of the hanger;

Fig. 5 is a top plan elevational view of the trouser supporting bar, the view being partly broken away;

Fig. 6 is an enlarged cross sectional view of the trouser supporting bar, the view being taken on the line 6—6 of Fig. 1; and

Fig. 7 is an enlarged fragmentary sectional view of a modified form of the invention wherein the hanger consists of a tubular body that receives therein the moth balls.

In the accompanying drawing wherein for the purpose of illustration is shown a preferred embodiment of my invention, the reference character A designates as a whole a hanger constructed in accordance with my invention, the main body portion of said hanger being preferably made of transparent material and embodying in its construction side arms 7 and 8 that are equipped with recesses 9 and 10 that retain therein a plurality of moth balls, indicated by the reference character B. By constructing the main body portion out of transparent material the number and size of the moth balls

therein will be apparent. It will be noted that openings 11 are provided in the upper extremities of the arms 7 and 8 in order that the moth balls may be placed in the recesses 9 and 10. This feature of construction is illustrated to advantage in Fig. 1 of the drawing. It is obvious that a cover can likewise be employed to prevent the moth balls from being dislodged from the arms.

In order to permit the fumes or gases to pass from the moth balls to the garment supported on the arms, I employ a plurality of spaced openings 12 in communication with said recesses 9 and 10.

Secured to the lower ends of the arms by wires or a like securing means 13 are the respective ends of a cross bar 14, which cross bar serves as a trouser or like garment supporting bar. This bar is preferably made of wood and has provided therein tapered openings 15 in which moth balls C of a smaller diameter than the moth balls A are placed. Openings or apertures 16 are likewise provided in the circular cross bar so that the fumes from the disintegrating moth balls may likewise pass to the garment.

In order to prevent accidental displacement of the moth balls from the trouser supporting bar 14, I have provided a perforated metallic shield 17 that is in frictional contact with said supporting bar. Due to the perforations provided in both the cross bar and the shield, the fumes can likewise escape and pass to the suspended garment. The moth balls are thus separately retained within the bar.

In the modified form of the invention disclosed to advantage in Fig. 7, I propose to make the entire hanger of a tubular construction and form the main body portion 18 of the hanger integral with the tubular supporting bar 19. Accordingly, the moth balls can readily be positioned in both the body 18 and the bar formation 19. Likewise, spaced perforations 20, as in the preferred form of the invention, permit the passage of the gases or fumes to the suspended garments.

From the foregoing description considered in connection with the accompanying drawing, it will be obvious that I have devised a simplified construction of a garment hanger wherein disinfectant means can be employed to readily eliminate troublesome moths.

It is to be understood that the forms of my invention herewith shown and described are to be taken as preferred examples of the same and

that various changes relative to the material, size, shape and arrangement of parts may be resorted to without departing from the spirit of the invention or the scope of the subjoined claims.

Having thus described my invention, I claim:

1. A garment hanger embodying in its construction a main body portion and a suspended circular bar, moth ball retaining recesses provided in said body portion and in communication with outlets for conveying fumes from the recesses to a suspended garment, said bar having tapered openings therein for retaining an auxiliary supply of moth balls, and a perforated circumferentially adjustable cover for removably 15 keeping the moth balls in the tapered openings provided in the suspended bar.

2. A garment hanger embodying in its construction a main body portion and a suspended bar, moth ball retaining recesses provided in said body portion and in communication with outlets for conveying fumes from the recesses to a suspended garment, said entire main body portion being constructed of transparent material whereby the size and number of the moth balls therein are clearly apparent, means in the suspended bar for separately retaining individual moth balls therein, and a perforated adjustable cover on the bar for keeping the moth balls within the bar in their respective positions.

SIDNEY M. ABBENS.
